UNITED STATES PATENT OFFICE

LESLIE CRANE, OF RUTLAND, VERMONT, ASSIGNOR OF ONE-HALF TO F. R. PATCH
MANUFACTURING COMPANY, OF RUTLAND, VERMONT, A CORPORATION OF VER-
MONT

POLISHING MACHINE

Application filed June 16, 1923. Serial No. 645,828.

This invention relates to certain new and useful improvements in polishing machines and more particularly to that type of machine in which a swinging arm carrying a polishing disc is mounted on a vertical standard, the object being to provide means for mounting the arm and for raising and lowering the same in position to operate on the material in the working area of the arm.

10 A further object of the invention is to provide a polishing machine in which a central standard is mounted rigidly within a base and has mounted thereon a head carrying an electric motor and an adjustably mounted 15 sectional arm having a polishing disc which is driven by the electrical motor in connection with novel means for raising and lowering the sectional arm in the form of a frictional means which is under the control of 20 the operator.

A still further object of the invention is to provide a construction of polishing machine in which the working parts are enshrouded so as to protect the same from grit and dust, 25 thereby increasing the life of the machine.

Other and further objects and advantages of the invention will be hereinafter set forth and the novel features thereof defined by the appended claims.

30 In the drawings,

Figure 1 is a side elevation of a polishing machine constructed in accordance with my invention, partly in section;

Figure 2 is a vertical section through the 35 standard showing the manner of mounting the head and driving shaft support;

Figure 3 is a detail side elevation of a portion of the sectional arm, partly in section, showing the manner of operating the 40 raising and lowering mechanism;

Figure 4 is an enlarged section of the frictional drive for the raising and lowering mechanism; and

Figure 5 is a detail enlarged section of the 45 driving shaft supporting bearing.

In the drawing 1 indicates a base which is anchored to a foundation and is provided with an upwardly extending reinforced portion 2 having a tubular bore 3 into which is 50 driven a tubular standard 4 and secured by

pins 5 as clearly shown in Figure 2. Driven into the top of the standard 4 is a socket 6 provided with a shoulder 7 bearing on the upper end of the standard 4 as clearly shown. The socket 6 is annularly reduced as shown 55 at 8 into which is secured a sleeve 9 forming with the socket 6 an annular chamber 10 into which is adapted to extend a tubular portion 11 of a head 12, said tubular portion being provided with openings 13. The lower end 60 of the tubular portion is mounted on ball bearings 14 within the bottom of the chamber 10 which is adapted to receive a lubricant for keeping the bearings lubricated at all times.

Bolted to the head 12 is a collar 15 provided with an arm 16 on which is mounted an electric motor 17 provided with a driving pinion 18 adapted to engage a beveled gear 19 carried by driving shaft 20 mounted in a bearing 21 formed on the end of an arm 22 carried by the collar 15. The collar 15 carries a sleeve 23 which has its lower end arranged within a collar 24 having an annular extension 25 which extends into a cup 26 75 formed on the upper end of the extension of the base and in which are arranged roller bearings 27, said collar having a hood 28 extending down over the cup portion for protecting the same.

The collar 24 is provided with an arm 29 having a socket 30 at its outer end in which is arranged a ball thrust bearing 31 for the reduced end 20' of the driving shaft 20. The beveled pinion 18 and beveled gear 19 are enclosed by a housing as clearly shown so as to 80 protect the same from the grit and dust of the machine when in operation.

The construction thus far described forms the main standard on which the head is revolvably mounted carrying the motor and driving shaft so that the swinging sectional arm hereinafter fully described will swing around the standard and by forming the standard hollow in the manner shown, the electric wires for the motor can be extended up through the base.

Slidably mounted on the sleeve 23 between the collars 15 and 24 is a tubular portion 32 of an arm 33 which is provided with exten- 100

sions 34 and 35 terminating in sleeve portions through which the drive shaft 20 extends and between which is mounted a drive pulley 36 which is feathered on the drive shaft 20 so that it moves up and down with the tubular portion of the arm. Mounted within the arm 33 is a stationary screw 37 which has its upper end secured in a socket 16' of the arm 16 and on which is mounted a nut 38 provided with a beveled gear 39 engaged by a beveled pinion 40 carried by a shaft 41 mounted in bearings 42 and 43 secured to the arm 33 as clearly shown in Figure 1. The gears 39 and 40 are enclosed by a housing as clearly shown.

15 The outer end of the arm 33 terminates in tubular portions 44 and 45 in which are mounted bearing sleeves 46 and 47 on which are pivotally mounted the tubular portions 48 of a frame 49, which is provided with bearings 50 at its outer end in which is slidably mounted a shaft 51 carrying at its lower end a polishing disc 52, which is raised and lowered by a lever 53 under the control of the operator.

25 Revolubly mounted in the bearing sleeves 46 and 47 is a tubular driven shaft 54 on which is feathered drive pulleys 55 and 56, pulley 55 being driven by a belt 57 from the driving pulley 36 and the pulley 56 carries a belt 58 which passes over a pulley 59 mounted on the shaft 51 in the outer frame 49.

The upper end of the driven shaft 54 is reduced as shown at 60 on which is mounted spaced beveled gears 61 and 62 provided with frictional cup portions 63 and 64 having conical inner faces adapted to be engaged by a frictional drive member 65 keyed on the extension 60 of the shaft 54 through the medium of a pin 65' working through an oppositely disposed slot in the extension 60 and carried by a shaft 66 extending up through the tubular driven shaft 54. The shaft 66 is provided with a collar 67 at its lower end provided with oppositely disposed pins which are engaged by the bifurcated arms of a yoke 68 pivotally mounted in a bracket 69, the opposite end of the yoke being provided with a bifurcation 70 into which extends the rounded end of a bell crank 71 mounted in the bracket 69, said bell crank being operated by a rod 72 through the medium of a lever 73 arranged in position to be readily manipulated by the operator.

55 The shaft 41 has secured to its end a gear 74 meshing with the pinions 61 and 62 so that as the shaft 66 is raised and lowered through the operating means controlled by the lever 73, the frictional member 65 can be thrown into contact with either of the inner faces of the cups 63 or 64 whereby the shaft 41 will be rotated in either direction in order to rotate the screw 38 in either direction so as to raise and lower the arm 33 in order to position the

polishing disc in respect to the work being operated on.

This frictional driving means is enclosed by a housing as clearly shown and provides a novel construction in raising and lowering the swinging arm of the polishing machine which is positive in operation.

In Figure 3 of the drawing I have shown the frictional member 65 arranged in a neutral position to allow the driven shaft 54 to rotate without operating the nut 38 working on the screw 37 and by either raising or lowering the lever 73, the frictional member 65 can be thrown into engagement with either of the frictional cups so as to rotate in the desired direction, which in turn rotates the shaft 41 and through the beveled gears 39 and 40, the nut 38 is rotated so as to either raise or lower the frame of the polishing machine.

80 In machines of this character it is desirable to form a construction in which the swinging frame can be rotated around a standard and as the weight is not equally distributed in view of the length of the sectional arm, it is desirable to provide means for taking care of the side thrust, which I have accomplished and by the particular manner of mounting the parts, the machine is balanced.

85 The head 12, collar 15, sleeve 23 and collar 24 constitute what I have termed a body, which is revolubly mounted on the standard on ball bearings so that the same can swing around the standard freely, the sleeve 23 constituting a guide on which the tubular portion of the working arm is slidably mounted.

90 What I claim is:

1. In a polishing machine, the combination with a standard, of a body mounted on said standard comprising spaced collars connected by a sleeve, one of said collars being secured to a head, the upper collar being provided with oppositely disposed arms and the lower collar with an arm, a shaft mounted in the arms of said collars, an electric motor carried by one of said arms, a driving connection between said electric motor and said shaft and a working arm slidably mounted on the connecting sleeve.

105 2. An electric polishing machine having a tubular fixed standard carrying a body provided with an electric motor, said body having a driving shaft on one side of said standard and a fixed screw on the other side, a driving connection between said motor and said driving shaft, an arm slidably mounted on said body carrying a nut working on said screw, a second arm carried by the outer end of the first mentioned arm provided with a polishing disc, a driving connection between said polishing disc and said driven shaft and frictional driving means for driving said nut for raising and lowering said arm.

115 3. In a polishing machine, the combination with a fixed tubular standard, of a cylindrical body revolubly mounted concentrically

- on said standard, thrust and radial bearings carried by said standard for said body, arms provided with bearings carried by said body, a driving shaft mounted in said bearings, an electric motor carried by said body, a direct driving connection between said electric motor and said driving shaft, a working arm slidably mounted on said body provided with a grinding tool and means for driving said tool from said driving shaft.
- 5 4. A polishing machine having a revolubly mounted body carrying a fixed screw, an arm slidably mounted on said body carrying a nut for working on said screw for raising
- 10 and lowering said arm, a second arm carried by the free end of the first-mentioned arm provided with a polishing disc, a tubular driven shaft, means for driving said polishing device from said tubular shaft, pinions
- 15 mounted on said shaft provided with internal cup portions, an operating shaft mounted in said tubular shaft having a double conical frictional member adapted to cooperate independently with said frictional cup portions of said pinions, a shaft for driving said nut and a gear carried by said shaft meshing
- 20 with said pinions.
- 25 In testimony whereof I hereunto affix my signature.
